UNITED STATES PATENT OFFICE.

HERMAN L. KUTTER, OF HAMILTON, OHIO.

SUCTION DEVICE FOR PRESS ROLLS AND THE LIKE.

Application filed December 21, 1921. Serial No. 523,862.

To all whom it may concern:

Be it known that I, HERMAN L. KUTTER, a citizen of the United States, and resident of Hamilton, in the county of Butler and the State of Ohio, have invented a certain new and useful Improvement in Suction Devices for Press Rolls and the like, of which the following is a full, clear, concise, and exact description, reference being had to the accompanying drawings, forming a part of this specification.

In the manufacture of paper, after the sheeted pulp or paper has passed the couch rolls it is conveyed on a traveling felt between one or more pairs of press rolls for the purpose of squeezing the water out of the paper and further compressing its fibers. Both the felt and the paper are very wet as they approach the press rolls and it is found in practice that a very considerable amount of water collects in the space between the approaching surfaces of the rolls, probably due partly to the forward revolution of the lower roll and partly to the attraction or action of the traveling felt. As a consequence, both the felt and paper are required to pass through a water bath just before passing through the press rolls. The present invention provides means for preventing the collection of water in the space between the upper and lower press rolls, with the result that the paper will leave the press rolls much drier than otherwise while the felt will be maintained in better condition and its life considerably prolonged.

The invention is also applicable to other parts of paper making machines where a similar condition exists, such as the couch rolls of a Fourdrinier machine. In the latter case the sheet of stock is carried through opposing couch rolls on a wire cloth and the necessity for the removal of water accumulating between the rolls is the same as in the case of press rolls.

In the drawings, which illustrate a preferred embodiment of the invention in association with press rolls,

Figure 1 is an end elevation of a press embodying the present invention.

Figure 2 is a broken vertical section through the rolls and the suction device.

Figure 3 is a plan view on the line 3—3 in Figure 2.

Figures 4 and 5 illustrate the preferred means for mounting the suction device in the press.

The press comprises a pair of rolls 1 and 2 which may be suitably mounted in any usual or desired way. Figure 1 illustrates a well known press housing in which the lower roll 2 is mounted in bearings secured in standards 3 that are supported by the frame 4. The upper roll 1 is mounted in bearings secured in arms 6 which are pivoted to the side members 5 of the frame and adapted to force the upper roll against the lower roll with varying pressure. The felt 7 carrying the sheet of paper 8 is guided over the roll 9 and then passes between the rolls 1 and 2 of the press. It is well known in paper mill practice that water collects in the space 10 between the approaching surfaces of the rolls and forms there what practically amounts to a pool of water through which the felt and paper must pass on their way between the rolls. The primary object of the present invention is to prevent such collection of water by utilizing the approaching surfaces of a pair of rolls, or of a traveling felt or other support and the opposing one of a pair of rolls, to form the space between the approaching surfaces into a vacuum chamber from which the water is exhausted.

The preferred means of accomplishing this end includes a chamber 11 which is preferably of substantially the same length as the rolls themselves. This chamber may be supported in any suitable way but preferably it is mounted in the manner illustrated in Figures 4 and 5. In this preferred way of mounting the chamber, brackets 12 are secured to the opposite side members 5 of the housing frame and a shaft 13 is journaled in the brackets and extends parallel to the press rolls. Arms 14 are keyed on the shaft 13 at its respective ends and at their free ends the arms 14 have pivotal connections 28 with the opposite end walls of the chamber 11. The pivotal connections 28 are so located that the suspended chamber 11 is substantially balanced. At one end of the shaft 13 an arm 29 is keyed on the shaft and is provided at its free end with oppositely faced bearing surfaces 30. The adjacent bracket 12 is provided with spaced bosses 31 embracing the end of the arm 29. Adjusting screws 32 are threaded through the bosses and their ends bear against the bearing surfaces 30. By the means described the chamber 11 may be accurately positioned with respect to the press rolls.

The chamber 11 is connected at one end with a pipe 15 flexibly leading to a suction pump 27. The chamber is formed so that it may extend into the space between the approaching surfaces of the press rolls and it is preferably formed with flat parallel walls 16 and 17 along its front edge spaced apart to form a slot 18 extending from the space 10 to the interior of the chamber. A bar 19 is secured to the chamber along one side of the slot and the blade 20 is secured to the chamber along the other side of the slot, the slot 18 and also the bar 19 and the blade 20 being preferably of substantially the same length as the rolls. The bar and blade may be conveniently secured to the chamber by screws 22 extending through the blade, the walls 17 and 16 of the chamber and into the bar 19. The blade 20 is formed with a beveled front edge 21 having a substantially air-tight bearing against the surface of the roll 2. The bar 19 is formed with a rounded surface normally bearing the felt and paper against the upper roll 1 in substantially air-tight relation. In some instances, particularly with respect to the succeeding pairs of a series of pairs of press rolls, the general arrangement of the press mechanism will make it impractical to have the bar 19 bear against the upper roll through the interposed felt and paper. In such instances the bar 19 will have a sufficiently air-tight bearing against the felt without bearing the latter against the roll, especially so since the general arrangement of the press mechanism maintains the traveling felt substantially taut. When used in connection with couch rolls, the bar 19 bears against the wire cloth and the ingress of air is practically and sufficiently prevented by the sheet of stock supported on the wire cloth. It will also be appreciated that the present invention may be usefully applied to a pair of rolls having no interposed felt or other support but in which it is desired to draw away water collecting between the rolls. It will be understood, therefore, that wherever it is stated that the present device bears against a roll, the bearing may be directly against the surface of the roll or indirectly through an interposed felt or other support. On the other hand, where it is stated that the bearing is against a traveling felt or other support, it will be understood that the bearing may be against the felt or other support alone or against a felt or other support interposed between the bearing device and the surface of the roll.

Each end wall of the chamber 11 is provided with guides 23 in which a plate 24 is slid able, the plates 24 being provided with slots 25 engaged by securing bolts 26. The plates 24 bear against the ends, that is the lateral edges, of the felt and against the ends of the rolls, the bar 19 and the blade 20,

and may be adjusted to vary the extent of the openings at the ends of the space 10 in order to regulate the volume of air admitted to the chamber and thus to control the effective suction through the chamber.

When the chamber is secured in proper position so that the bar 19 and blade 20 effectively bear against the rolls, or against the traveling felt and the lower or opposing roll, operation of the pump will maintain suction in the chamber and from the space formed between the bar and blade and the cooperating surfaces of the press mechanism. These surfaces themselves are thus made to cooperate in forming the space between the rolls into a suction chamber so the water, instead of being allowed to collect between the rolls is drawn out into the chamber from which it is discharged.

What I claim is:

1. In a machine of the class described, the combination of two members having opposing traveling surfaces, a chamber having a mouth with the lips thereof bearing against the respective surfaces to form an inclosure and having an air admission opening, means for exhausting air from the chamber, and means for adjusting the air admission opening.

2. In a machine of the class described, the combination of a pair of revoluble rolls, a chamber having a mouth with the lips thereof bearing against the respective rolls to form an inclosure and having an air admission opening, means for exhausting air from the chamber, and means for adjusting the air admission opening.

3. In a machine of the class described, the combination of a pair of revoluble rolls, a traveling support extending between the rolls, a chamber having a mouth with the lips thereof bearing respectively against one of the rolls and the support to form an inclosure and having an air admission opening, means for exhausting air from the chamber, and means for adjusting the air admission opening.

4. In a machine of the class described, the combination of a pair of revoluble rolls, a traveling support extending between the rolls, a chamber having a mouth of substantially the same length as the rolls, a bar secured along one lip of the mouth and having a rounded surface bearing against the support, a blade secured along the other lip of the mouth and bearing against the lower roll, and means for exhausting air from the chamber.

5. In a machine of the class described, the combination of a pair of revoluble rolls, a traveling support extending between the rolls, a chamber having a mouth of substantially the same length as the rolls, a bar secured along one lip of the mouth and having a rounded surface bearing against the

support, a blade secured along the other lip of the mouth and bearing against the lower roll, the chamber having an air admission opening, means for exhausting air from the 5 chamber, and a plate adjustably secured to the chamber over the air admission opening.

6. In a machine of the class described, the combination of a pair of revoluble rolls, a traveling support extending between the 10 rolls, a chamber supported on a pivotal axis parallel with the rolls, the chamber having a mouth with the lips thereof bearing respectively against one of the rolls and the support to form an inclosure, means for exhausting air from the chamber, and means 15 for adjusting the chamber toward and from the rolls.

7. In a machine of the class described, the combination of a pair of revoluble rolls, a traveling support extending between the 20 rolls, a chamber supported on a pivotal axis parallel with the rolls, the chamber having a mouth with the lips thereof bearing respectively against one of the rolls and the support to form an inclosure and having an air admission opening, means for exhausting air from the chamber, means for adjusting the chamber toward and from the rolls, and means for adjusting the air admission 25 opening.

8. In a machine of the class described, the

combination of a housing, a pair of revoluble rolls supported thereby, a traveling support extending between the rolls, an arm pivoted to the housing on an axis parallel with the 35 rolls, means for adjusting the arm on its axis, a chamber suspended from the arm on a pivotal axis parallel with the rolls, the chamber having a mouth with the lips thereof bearing respectively against one of the 40 rolls and the support to form an inclosure, and means for exhausting air from the chamber.

9. In a machine of the class described, the combination of a housing, a pair of revoluble rolls supported thereby, a traveling support extending between the rolls, an arm pivoted to the housing on an axis parallel with the 45 rolls, means for adjusting the arm on its axis, a chamber suspended from the arm on a pivotal axis parallel with the rolls, the chamber having a mouth with the lips thereof bearing respectively against one of the 50 rolls and the support to form an inclosure and having an air admission opening, means 55 for exhausting air from the chamber, and means for adjusting the air admission opening.

In witness whereof, I hereunto subscribe my name this 12th day of December, 1921.

HERMAN L. KUTTER.
